UNITED STATES PATENT OFFICE

OLLIE M. BEALL, OF DES MOINES, IOWA

SOUND-PRODUCING TOY

Application filed May 13, 1929. Serial No. 362,758.

The principal object of this invention is to provide a novel instrument capable of producing sound when held in the hands and air blown through it.

5 A further object of this invention is to provide a device upon which a tune may be played.

A still further object of my invention is to provide a musical instrument that is economical in manufacture and durable in use.

10 These and other objects will be apparent to those skilled in the art.

My invention consists in the construction, arrangement and combination of the various 15 parts of the device, whereby the objects contemplated are attained as hereinafter more fully set forth, pointed out in my claims and illustrated in the accompanying drawings, in which:

20 Fig. 1 is a perspective view of my invention properly held in the hands of the operator and ready for use.

Fig. 2 is a side view of the musical instrument with dotted lines to more fully 25 illustrate its construction.

Fig. 3 is a bottom view of my invention.

This device is designed to be used in combination with the hands for producing the various notes and tone values and is so simple in construction and design that it may 30 be easily carried in the pocket. Also, due to its construction, it is easily kept clean and sanitary, thereby making it an ideal article for children.

35 I have used the numeral 10 to designate the base portion having the opening 11. Integrally formed on this base portion and extending laterally from the opening 11 is the portion 12 designed to be grasped between the thumb and forefinger of the left hand as shown in Fig. 1. Extending downwardly from the opposite marginal edge of the base member and curved around the forward portion of the opening 11 is the 40 wall 13 as shown in Fig. 3. The rear portion of the base portion is pointed to allow the two thumbs of the user to meet. The forefinger of the left hand rests around the forward end of this wall 13 and all of the 45 fingers are grasped by the right hand as

shown in the drawing. By this arrangement, the inner side of the thumb of the right hand will rest on the wall 13, thereby creating with the base portion a cavity. The numeral 14 designates a pipe formed by bending a portion of the forward end of the base member, and having one end termination adjacent the opening 11.

55 By this construction, it will readily be seen that I have provided a musical instrument that may be fabricated from a single sheet of material. By holding the device in the hands, as heretofore described, and blowing through the forward end of the pipe 14, sound notes will be produced. If 60 the dimensions of the cavity obtained by the device and hands are changed or an outlet from the cavity is obtained by opening and closing the hands, various musical notes may be obtained.

65 Sound, by blowing through the pipe, may also be obtained by the use of only one hand if the same is so placed around the under side of the base portion that a cavity communicating with the opening 11 is obtained.

If it is desired, a rubber tube 15 may be used, having one end around the forward end of the pipe 14 and its other end designed to be placed in the mouth of the operator. This tube may be any length desired.

70 The device also makes a most excellent whistle.

75 Some changes may be made in the construction and arrangement of my musical instrument without departing from the real spirit and purpose of my invention and it is my intention to cover by my claims any modified forms of structure or use of mechanical equivalents which may be reasonably included within their scope.

80 I claim:

85 1. In a device of the class described, a base member having an opening and designed to be held between the two hands of the operator, a projection on the said base member designed to rest between the thumb and forefinger of the operator, and a pipe secured to said base member and terminating adjacent said opening.

90 2. In a device of the class described, a

base member having an opening, a circular wall secured to said base member and embracing a side portion of said opening, and a pipe terminating adjacent said opening.

5 3. In a device of the class described, a base member having an opening, a downwardly extending wall at one side of said base member and embracing a portion of said opening, and a pipe having one end terminating adjacent said opening.

10 4. In a device of the class described, a base member having an opening, a wall secured to said base member and embracing a side portion of said opening, and a pipe terminating adjacent said opening.

15 5. In a device of the class described, a base member having an opening and designed to be held between the two hands of the operator, a projection on said base member designed to rest between the thumb and forefinger of the operator, a pipe secured to said base member and having one end terminating adjacent said opening, and a flexible tube communicating with the opposite end of said pipe.

20 6. In a device of the class described, a base member having an opening, a pointed end integrally formed on the rear end portion of said base member, a projection on said base member designed to rest between the thumb and forefinger of the operator, and a pipe secured to said base member and terminating adjacent said opening.

OLLIE M. BEALL.
